UNITED STATES PATENT OFFICE.

CHARLES D. SEEBERGER, OF YONKERS, NEW YORK.

CONVEYER.

No. 888,654.

Specification of Letters Patent.

Patented Dec. 18, 1906.

Application filed May 28, 1902. Serial No. 109,287.

To all whom it may concern:

Be it known that I, CHARLES D. SEEBERGER, a citizen of the United States, residing at Yonkers, in the county of Westchester and State of New York, have invented certain new and useful Improvements in Conveyers, of which the following is a specification.

My invention is concerned with certain improvements in conveyers, and particularly with moving stairways in which the tread-surfaces of the steps form a continuous level surface on the landings and a series of steps on the inclined portions of the tracks upon which they run, and is designed to produce a device of the class described in which the steps can transport either on the ascending or descending portion with but a single riser for each step instead of the two risers which have heretofore been necessary when a single set of steps were arranged to transport on both the ascending and descending inclines. In order to effect this desired result with a single riser, and thus obviate some of the disadvantages arising from the use of two risers on each step, I employ a single riser on each step, preferably pivoted thereto and arranged so that it is automatically moved from the front to the rear side or edge of the step as it passes over a landing or portion of the track connecting ascending and descending portions of the track, and vice versa.

To illustrate my invention, I annex hereto two sheets of drawings, in which the same reference characters are used to designate identical parts in both sheets, of which—

Figure 1 is a side elevation, in a somewhat diagrammatic form and with portions broken away, of a conveyer containing my improvements. Fig. 2 is an inverted plan view, on an enlarged scale, of a step, together with a part of the associated housing, showing an embodiment of my present invention. Fig. 3 is a top plan view of the same parts, together with a drive mechanism, on a larger scale. Fig. 4 is a rear elevation of the parts shown in Fig. 3, with the tracks added; and Fig. 5 is a vertical section on the line 5 of Fig. 3, but on a still larger scale.

In carrying out my invention I preferably employ the four-wheeled type of truck, such as is shown, and in which the forward wheels roll upon the inner pair of tracks 11, while the rear wheels 12 roll upon the outer tracks 13, these tracks being in different horizontal planes on the inclined portions of the ways

on which they form steps, in order to keep their tread-surfaces horizontal, while they are on the same horizontal plane on the landings and preferably on the same horizontal plane on the curves constituting the ends and the unused portions of the tracks. Of course it will be understood that I may employ an arrangement of tracks and trucks in which the front and rear wheels are normally on different levels and in which the inner and outer tracks are in the same horizontal plane on the inclined portions and in different planes on the other portions, being the reverse construction from that illustrated, and that I may employ but a single pair of wheels for each step.

The wheels 10 and 12 are shown as mounted on the arms 14, which are preferably rigidly secured to the brackets 15, constituting the ends of the steps. These brackets 15 are surmounted by the rectangular frame 16, into which is set the plate 17, constituting the main portion of the tread-surface of the step. Upon the stub-shafts 18, connecting and between the arms 14 and the brackets 15, I mount the links 19, which preferably have the rack-teeth 20 formed on the under surface thereof, so that the links are, in effect, rack-bars, to which one or more spur-gears 21 are applied on both sides of the steps at any necessary points to drive the same. As the various spur-gears 21 are rotated in unison, it will be apparent that the steps will be driven forward at a certain fixed rate of speed.

Mounted to slide and rotate in suitable bearings 22 and 23, the position of which is indicated in dotted lines in Fig. 3 and which are formed in the brackets 15, is the rock-shaft 24, which has rigidly secured thereto the pair of brackets 25, upon the outer ends of which is secured the reversible riser 26, which preferably has its surface curved for the customary reason. This riser while traveling upon the ascending inclined portion 27 of the tracks occupies the position shown at the left side of Fig. 1 and in full lines in Fig. 5, and as it passes some point in the upper landing, as at 28, it is automatically shifted to the position shown at the right side of Fig. 1 and in dotted lines in Fig. 5 by the mechanism hereinafter described, the steps being assumed to run from left to right in Figs. 1 and 5, although of course they may travel in either direction. On the descending inclined portion 29 of the tracks and

around the lower end of the tracks the riser occupies its dotted-line position; but at some convenient position before the ascending incline 27 is reached, as at 30, it is shifted again to the full-line position, which it occupies until it reaches the point 28 again, where it is again reversed. The mechanism for automatically effecting this reversal is best shown in Figs. 3 to 5, where it will be seen that on the under surface of a convenient portion 31 of the housing in which the system is inclosed I locate a sufficient number of rack-teeth 32 to engage with the spur-gear 33, secured upon the outer end of the shaft 24. The number of the teeth 32 at each shifting-point 28 and 30 is just sufficient to rock the shaft 24 through the necessary angular distance to carry the riser 26 from one position to the other.

To lock the riser in either position which it may assume, I place upon the shaft 24 a pin 34, which is adapted to coöperate with the slot 35 or 36, as the case may be, formed in one face of the bracket 37, secured on the under side of the tread portion 17 of the step and in which the shaft 24 is journaled. A helically-coiled expanding-spring 38, secured at one end of the shaft 24, is interposed between the bearing 22 and the adjacent bracket 25 in such a position that it holds the shaft 24 normally in the position shown in full lines in Fig. 4 and tends to return it to said position when it is displaced. To move this shaft 24 automatically to the dotted-line position of Fig. 4 at each of the shifting-points 28 and 30, I employ a cam-surface 39, formed on the housing 31 in position to coöperate with the end of the shaft 24, and cam it to its dotted-line position, where the gear 33 is engaged by the teeth 32 and the riser is rocked into the other position, in which it is locked immediately the rack-teeth 32 are passed by the action of the spring 38 in throwing it back longitudinally to normal position, (shown in full lines in Fig. 4,) in which the pin 34 will engage the other one of the slots 35 or 36 to hold the parts locked. To prevent the shaft returning to its normal position under the stress of the spring 38 before the shifting of the riser is completed, I form adjacent to the rack-teeth 32 an engaging surface 40 (shown in dotted lines in Fig. 3) parallel thereto and which may be considered as a continuation of the cam-surface 39.

By the mechanism herein shown and described it will be apparent that I am enabled to employ a single riser for each step upon ascending or descending portions of the run, and it will be apparent that as many of these inclined portions may be employed as may be desired, it only being necessary to insert the shifting controlling mechanism at some convenient point between each ascending and descending inclined portions.

While I have shown my invention as em-

bodied in the form which I at present consider best adapted to carry out its purposes, it will be understood that it is capable of modifications and that I do not desire to be limited in the interpretation of the following claims, except as may be necessitated by the state of the prior art.

What I claim as new, and desire to secure by Letters Patent of the United States, is—

1. In a device of the class described, a step having a single reversible riser adapted to coöperate with either side thereof for the purpose described.

2. In a device of the class described, a step having a reversible riser for the purpose described, and means for locking said riser in either position.

3. In a device of the class described, ways having ascending and descending inclined portions, a step adapted to move in said ways, and having a reversible riser.

4. In a device of the class described, ways having ascending and descending inclined portions, steps adapted to move in said ways, means for driving said steps, reversible risers secured to said steps, and means for automatically reversing said risers as the steps pass from an ascending inclined portion to a descending inclined portion of the tracks and vice versa.

5. In a device of the class described, ways having ascending and descending inclined portions, steps adapted to move in said ways, means for driving said steps, reversible risers on said steps, means for automatically reversing said risers as the steps pass from an ascending inclined portion to a descending inclined portion of the tracks and vice versa, and locking mechanisms for securing said risers in either position and retaining them until they are ready to be reversed.

6. In a device of the class described, ways having ascending and descending inclined portions, a step adapted to move in said ways, arms pivotally secured on the under side of a step, the riser secured to said arms, and means for holding said riser in either position of adjustment.

7. In a device of the class described, ways having ascending and descending inclined portions, a step adapted to move in said ways, a rock-shaft secured to said step, arms secured to the rock-shaft, a riser secured to the arms, means for rocking said shaft to bring the riser into coöperative relation with the front or rear of the step, and locking mechanism for securing said riser in either position of adjustment.

8. In a device of the class described, ways having ascending and descending inclined portions, a step adapted to move in said ways, a rock-shaft secured to said step, arms secured to the rock-shaft, the riser secured to the arms, means for rocking said shaft to bring the riser into coöperative relation with

- the front or rear of the step, and locking mechanism for securing said riser in either position of adjustment consisting of a bearing having slots therein, a pin 34 on the rock-shaft adapted to coöperate with said slots, and means for moving the shaft to bring the pin into and out of engagement with said slots.
9. In a device of the class described, ways having ascending and descending inclined portions, a step adapted to move in said ways, a rock-shaft mounted on said step and having a pinion secured thereto, arms secured to said shaft, a riser secured to said arms, locking mechanism for holding said riser in either position of adjustment, and racks adapted to coöperate with the pinion to rock said shaft.
10. In a device of the class described, ways having ascending and descending inclined portions, a step adapted to move in said ways carrying a rock-shaft having a pinion secured on one end thereof, and arms secured thereto and having a riser secured to their outer ends, bearings secured to said steps having slots thereon, a pin on the shaft adapted to coöperate with said slots, means for moving the shaft longitudinally to bring the pin into and out of engagement with the slots, and racks for engaging the pinion for the purpose described.
11. In a device of the class described, ways having ascending and descending inclined portions, steps adapted to move in said ways, rock-shafts secured in said steps having arms secured thereto, risers secured to said arms, means for rocking said shafts to shift the position of the risers, locking mechanisms for said risers, and means for disengaging the locking mechanisms.
12. In a device of the class described, ways having ascending and descending inclined portions, a step adapted to move in said ways, a slideable rock-shaft mounted on said step, a riser secured to said rock-shaft and adapted to move therewith into different positions, locking mechanism for said rock-shaft consisting of a bearing having slots therein, and a pin on the shaft, and means for moving the shaft to bring the pin into and out of engagement with the slots consisting of a cam coöperating with the end of the shaft to move the pin out of engagement and a spring coöperating with said shaft to move it to bring the pin into engagement.
13. In a device of the class described, ways, steps adapted to move in said ways, brackets forming a part of said steps, studs projecting outwardly from said brackets, wheels supported from the outer ends of said studs, and links pivoted on said studs and connecting the steps.
14. In a device of the class described, ways, steps adapted to move in said ways having brackets forming a part thereof, studs projecting outwardly from said brackets, wheels supported from the outer ends of said studs, rack-links pivoted to said studs and connecting the steps on both sides, and driving-pinions coöperating with said links on both sides of the steps.
15. In a device of the class described, ways having ascending and descending inclined portions, steps adapted to move in said ways having brackets forming a part thereof, studs projecting outwardly from said brackets, wheels supported from the outer ends of said studs, rack-links pivoted to said studs and connecting the steps on both sides, and driving-pinions coöperating with said links on both sides of the steps.
16. In a device of the class described, a step having a reversible riser, and means for automatically reversing the riser.
17. In a device of the class described, a step having a reversible riser, a lock for holding the riser in either position, and means for automatically unlocking and reversing the riser and locking it in reversed position.
- In testimony whereof I affix my signature in presence of two witnesses.
